CAN OPENING

Joseph R. Smith, Shreveport, La.

Application June 28, 1954, Serial No. 439,627

6 Claims. (Cl. 30—6.1)

This invention relates to can-opening devices and has for its primary object a can opener which can easily puncture the tops of cans with only the expenditure of a small amount of force.

A further object of my invention is the provision of a device as described which is durable and positive in operation.

A still further object is to provide a device as described which is portable, or may be permanently installed as desired.

A still further object of my invention is to provide a can-opening device encased in a housing to keep it clean and free of dust, dirt, etc.

A still further object is to provide a can-opening device which is safe in operation.

A still further object of my invention is to provide a cutter bar having integral cutting blades.

Other and further objects of the invention will appear from the following specification and claims.

The can openers in use today, especially the models for use where large quantities of canned drinks such as beer are opened, have many drawbacks, one of the most serious being that the force required to enable the cutter to penetrate the metal is so great that women or even men who use such devices soon tire and get blisters on their hands.

With the present invention, through a leverage and linkage system, only a very small amount of pressure is required to force the cutter to penetrate the top of the can.

Another drawback to the use of present day cutters of this type is the fact that the blades continually break and have to be replaced. The present invention overcomes these disadvantages and provides for an enclosed, durable, easily operated can opener which can be either portable or permanently mounted.

Referring to the drawing in detail in which like numerals represent like parts throughout the several views:

Figure 1 represents a front elevational view of the device ready for use.

Figure 2 is a side elevational view of the device with the housing removed.

Figure 3 is a rear elevational view of the device with the housing removed.

Referring to the drawings, the numeral 10 represents a base, having resilient feet 11 of rubber or other resilient material to give the device pressure absorbing means. Mounted on the base 10 is a bracket 12 having an in-turned flange 13 that is secured to the base 10 by bolts 14. A portion 15 of the bracket is bent inwardly and downwardly to form a U-shaped slot 16. Mounted in the slot 16 for free movement is one end of a handle shaft 17 that is secured in the slot by bolt 18, the opposite end of the handle shaft 17 being provided with a rubber or plastic grip 19.

Mounted on the base 10 in spaced relation are tubes 20 and 21, each being provided with caps 22 that may be screw threaded on the tubes, or they may be secured by other suitable means. A reinforcing bar 23 is supported

by the tubes, the portions resting on the caps being securely fixed by (screws not shown) or spot welded. It is to be understood that if desired, the tubes 20 and 21, caps 22, and bar 23 may be cast in one piece. Within each tube is a slot 24 that receives the ends 25 of a bar 26, the end edges 27 of the bar being spaced from the inner wall of the tubes. The bar 26 is provided with a vertical element or arm 28, the top edge 29 being provided with a cam surface 30. The bottom edge 31 of the bar 26 is provided with container piercing points 32 and 33, the portions 34 and 35 of the bottom edge engaged by the top end of springs 36, the springs being housed in the tubes 20 and 21, the lower ends of the springs engaging the top face of base 10.

Pivottally mounted on one end of a through bolt 37 on the outside wall of the tube 21, is one end of link 38, and passing through the slot 24 and into the tube 21, is one end 39 of link 40 that is mounted for pivotal movement on bolt 37. The end 41 of link 40 passes through a slot 42 in tube 20, and slot 42 in one of the caps 22 for accurate movement. To the end 41 of link 40 there is pivotally connected a sleeve 43 having an internal thread that receives the threaded end 44 of shaft 45, providing a means for adjustment between links 30 and 38. The end 46 of shaft 45 is pivotally connected to link 38 adjacent one end by a bolt 47 or other suitable means, and to the bolt 47 is attached one end 48 of spring 49, the opposite end 50 engaging an aperture in the bar 23. The end portion 51 of link 38 is slightly curved, and at the end of the link there is secured by nuts 52 on the shank of a ball and socket joint 53, a sleeve 54 having an internal thread that receives the threaded end 55 of rod 56, the opposite end 57 of rod 56 being also threaded and it is engaged by internal threads in sleeve 59; the sleeve having a ball and socket joint 58 that is connected to and secured to the handle shaft 17 by nuts 60 on the shank 61. The threaded ends of rod 56 provides a means for adjustment between handle shaft 17 and link 38.

The bracket 18 and the tubes 20 and 21, and the associated mechanism are enclosed by a cover 63, the cover being provided with a slot 64 in which link 17 of handle 19 may operate. Within the wall of the housing or cover there is an opening 65, and in the opening there is positioned a semi-circular plate 66 having flanges 67 that are secured to the inner wall of the housing by lock screws 68.

In the operation of the device, a can containing liquid therein is placed in the opening 65 until the wall of the can impinges the wall of the semi-circular plate 66. In this position the can is within the housing or cover 63. Downward movement of the handle exerts a pull on the sleeves 57, 54 and shaft or rod 56 imparting a pull on link 38, which in turn imparts movement to shaft or rod 45 and sleeve 43, which in turn imparts a downward pull on link 40. During this movement the ball and sockets 53 and 58 yield, as well as compression spring 49. During downward movement of link 40, the lower edge of link 40 impinges the cam surface 30 forcing the bar 26 downwardly, the points 32 and 33 on the bar piercing the top end of a can, making openings in the top of said can. Downward movement of the bar 26 compresses springs 36. After the top of the can has been pierced, the handle is released and the springs 36 which have been compressed, now force bar 26 upwardly, the cam surface 30 forcing link 40 upwardly, link 40 in turn lifting sleeve 43 and rod 45, spring 49 assuming its normal position, and together with shaft 45 lifting link 38 upwardly, the movement of ball and socket 53 carrying with it sleeve 54, rod 56 and sleeve 59, sleeve 59 moving on ball and socket joint 58 connected to arm 17, arm 17 then lifted to a position where it is ready for the next downwardly push.

Changes in details and construction may be made without departing from the spirit of the invention.

What is claimed is:

1. A can opening device comprising a base, a pair of tubes and a bracket on said base, a strap secured to the top of said tubes to hold said tubes in spaced relation, slots in said tubes, a bar interposed between said tubes and having its end portions extending into said slots and tubes, actuating means connected to one of said tubes, means on said bar responsive to said actuating means, and means on said bar for opening a can. 10
2. A can opening device comprising a base, a pair of tubes and a bracket on said base, a strap secured to the top of said tubes to hold said tubes in spaced relation, slots in said tubes, a bar interposed between said tubes and having its end portions extending into said slots and tubes, actuating means connected to one of said tubes, 15 means on said bar responsive to said actuating means, means on said bar for opening a can, and means in said tubes to normally hold said bar in an inoperative position.
3. A can opening device comprising a base, a pair of tubes and a bracket on said bar, a strap secured to the top of said tubes to hold said tubes in spaced relation, slots in said tubes, a bar interposed between said tubes and having its end portions extending into said slots and tubes, actuating means connected to one of said tubes, 20 means on said bar responsive to said actuating means, means on said bar for opening a can, means in said tubes to normally hold said bar in an inoperative position, a handle pivotally connected to said bracket, and means connecting said handle to said actuating means.
4. A can opening device comprising a base, a pair of tubes and a bracket on said base, a strap secured to the top of said tubes to hold said tubes in spaced relation, slots in said tubes, a bar interposed between said tubes and having its end portions extending into said slots and tubes, actuating means connected to one of said tubes, means on 25 said bar responsive to said actuating means, means on said bar for opening a can, means in said tubes to normally hold said bar in an inoperative position, a handle pivotally connected to said bracket, and means connecting said handle to said actuating means.

5

5. A can opening device comprising a base, a pair of tubes and a bracket on said base, a strap secured to the top of said tubes to hold said tubes in spaced relation, slots in said tubes, a bar interposed between said tubes and having its end portions extending into said slots and tubes, actuating means connected to one of said tubes, 10 means on said bar responsive to said actuating means, means on said bar for opening a can, means in said tubes to normally hold said bar in an inoperative position, a handle pivotally connected to said bracket, means connecting said handle to said actuating means, means interposed and connected to said actuating means at one end connecting said actuating means for pivotal movement when said handle is moved, and means interposed between said actuating means and said bar for supporting said actuating means in an inoperative position.
6. A can opening device comprising a base, a pair of tubes and a bracket on said base, a strap secured to the top of said tubes to hold said tubes in spaced relation, slots in said tubes, a bar interposed between said tubes and having its end portions extending into said slots and tubes, actuating means connected to one of said tubes, a handle pivotally connected to said bracket, adjustable means connecting said handle with said actuating means, 15 adjustable means connected to said actuating means at one end, means in said tubes responsive to movement of said bar, means on said bar for opening a can, and means connected to said strap and said actuating means to return from an operative position to an inoperative position said actuating means, adjustable means and said handle, the means in the tubes returning said bar to an inoperative position. 20
